Specification for Design.

Patented Dec. 30, 1913.

Application filed August 18, 1913. Serial No. 785,401. Term of patent 14 years.

To all whom it may concern:

Be it known that I, WILLIAM C. HENDRIE, a citizen of the United States, residing at Los Angeles, county of Los Angeles, State of California, have invented a new, original, and ornamental Design for Rubber Vehicle-Tires, of which the following is a specification, reference being had to the accompanying drawing, forming part thereof, where-

in—
Figure 1 is a view in perspective of a rubber vehicle tire, showing my new design.

Fig. 2 is a view in plan of a rubber vehicle tire tread, showing my new design.

I claim:

The ornamental design for a rubber vehicle tire, as shown.

In witness whereof I have signed my name to this specification in the presence of two witnesses.

WILLIAM CLYDESDALE HENDRIE.

Witnesses:
